By Robert A. Young Attorney

UNITED STATES PATENT OFFICE.

HAROLD W. WEBBE, OF COLUMBUS, OHIO.

RADIO SOUNDER AND INTERFERENCE ELIMINATOR.

Application filed June 18, 1923. Serial No. 646,045.

To all whom it may concern:

Be it known that I, HAROLD W. WEBBE, a citizen of the United States, residing at Columbus, in the county of Franklin and State of Ohio, have invented certain new and useful Improvements in Radio Sounders and Interference Eliminators, of which the following is a specification.

This invention relates to a radio sounder and interference eliminator which obviates the use of head sets and causes a signal to come in clear and distinct above ordinary interference.

In the use of audion bulbs as amplifiers it is well known that disturbances as well as signals are amplified at the same ratio. The disturbance or interference, therefore, may become so loud as to render the signal indistinct and at times unreadable, although the character of the signal has not been entirely wiped out.

This invention consists in stretching across the diaphragm of a receiver, a musical string preferably a steel "E" mandolin string. The wire bears slightly on a raised ridge in the center of the receiver diaphragm. A thumb screw is provided to tighten or loosen the wire. The receiver is connected to a radio power amplifier. By tuning into a continuous wave by the heterodyne method the signal is brought to its loudest pitch in the receiver. The wire is then tuned to resonance with this note, whereupon a distinct and clear musical signal rings out over and above any noises in the receiver, or the wire may be set and the receiver tuned to the wire. In either case the signal has now received an amplification at a greater ratio than the disturbance, since tube noises, static, spark, and other C. W. signals having a different pitch do not affect the wire. High frequency spark signals, such as Arlington time signals, etc., may be copied by this method when the spark frequency is in the musical range of the wire. The wire tends to dampen the diaphragm between signals, giving the signals a clear ring.

Another application of this general principle is to have the receiver free to move back and forth under the wire. Then by modulating the transmitting station signal

at an audio frequency the receiver is moved back and forth until the note of this note is reached when the wire goes into vibration. By this method a number of different messages may be transmitted on the same carrier. Furthermore, a head set may be attached to a contact just above the wire and a tone received when the wire engages the contact during its vibration, or the wire may be made to vibrate in the presence of a magnetic field.

In the drawings.

Figure 1 is a diagrammatic side view of the device showing the receiver in fixed position.

Figure 2 is a similar view showing the receiver free to move in the direction indicated by the arrow.

Figure 3 is a similar view showing the device connected to an audio amplifier and shows the receiver adapted to be either fixed or movable.

Figure 4 is a plan view of an experimental type of the device, showing the receiver in fixed position.

Referring with more particularity to the drawings, a Baldwin receiver 7 is placed under a vibrating wire 2. The wire rests lightly on a raised ridge 1 on the diaphragm of the receiver 7. The wire is further supported by the bridges 3-3 and held fast by set screws 6. Thumb screw 5 by means of a worm on post 4 tightens or loosens the wire.

Figure 2 shows a contact which engages the wire when in motion and gives a tone to the receiver 7. In this device the actuating receiver under the wire may move in either direction to locate the note of the incoming signal. This device, as shown in Figure 2 contemplates the use of modulated carrier waves. In Figure 3, the field of the receiver is brought into close proximity of the wire. When the wire is in vibration a pleasing musical signal is heard in the audio amplifier circuit. Since the wire is not affected by non-resonate disturbances, this device has a very high signal ratio over interference.

Having described my invention, I claim:

A radio sounder comprising, in combination, a telephone receiver provided with a diaphragm adapted to be vibrated by incoming signals, said diaphragm having a cen-

trally located raised ridge, a wire of considerable length stretched taut and arranged in proximity thereto and adapted to be vibrated thereby, a separate circuit in proximity to said wire including means for amplifying said signals, means for adjusting said wire so as to be in resonance with the receiver diaphragm and the incoming signals, said receiver being capable of being moved longitudinally in either direction 10 with relation to said wire.

In testimony whereof I affix my signature.

HAROLD W. WEBBE.
